UNITED STATES PATENT OFFICE.

THOMAS ARTHUR M. STEVENSON, OF WINSTON-SALEM, NORTH CAROLINA.

SMELTING-FURNACE.

1,269,974.

Specification of Letters Patent. Patented June 18, 1918.

Application filed March 29, 1917. Serial No. 158,230.

To all whom it may concern:

Be it known that I, THOMAS A. M. STEVENSON, a citizen of the United States, and a resident of Winston-Salem, in the county 5 of Forsyth and State of North Carolina, have invented a new and Improved Smelting-Furnace, of which the following is a full, clear, and exact description.

My invention has for its object to provide 10 a smelting furnace which is relatively cheap to construct, and which may be conveniently shipped, and be operated economically in small units.

The furnace is constructed with a shaft 15 having an air space which extends there-around and which serves to carry off the heat, thereby keeping the shaft at a normal temperature. The air which is heated around the shaft is led over the discharged 20 slag, after which the heated air is passed to twyers. Also, by this means the head units are saved which are wasted in the water in old type furnaces and the space is heated to a high temperature which may be used in 25 greater volume without chilling the furnace. A great saving in fuel is thereby effected.

Additional objects of the invention will appear in the following specification, in which the preferred form of the invention is 30 disclosed.

In the drawings similar reference characters denote similar parts in all the views, in which—

Figure 1 is a sectional elevation of the invention; and

Fig. 2 is a sectional view on the line 2—2 of Fig. 1.

By referring to the drawings, it will be seen that the furnace is constructed with a 40 compartment 5 having an opening 6, a shaft extending upwardly from the top of the compartment and being provided with an inner wall 7 and an outer wall 8 spaced therefrom, forming an air space 9. The inner wall 7 is secured to the top of the compartment 5 around the opening 6. A cold air conduit 10 is mounted on the top of the compartment 5, and is disposed around the bottom of the shaft, there being an opening 45 11 at the bottom of the outer wall 8 of the shaft, so that the air from the cold air conduit 10 may pass upwardly in the air space 9. Air is fed to this cold air conduit from an opening shown by the dotted lines 12, 50 and, if desired, by means of a blower not shown,

It will be understood that as cold air passes at all times upwardly against the inner wall 7 of the shaft, it will be impossible for the inner wall 7 of the shaft to 60 become unduly heated, and that the air which passes to a hot air conduit 13 from the top of the air space 9, will be heated by contact with the inner wall 7 of the shaft. By means of this construction, the shaft 65 may be made of relatively light material, thereby making it possible to ship the furnace conveniently in small units which may be used at the mines, thereby permitting the reduction of ores at the mines. The inner wall 7 of the shaft is corrugated vertically, which increases the strength of the shaft and increases the area of the cooling 70 surface.

In addition to the opening 6 in the compartment 5, there is another opening 14, the hot air conduit 13 having a terminal 15 which extends down through this opening 14 over a fore-hearth car 16 which is provided for receiving slag from the crucible 80 car 17, this crucible car 17 being provided with an outlet 18 leading to the fore-hearth car 16. The air which passes through the hot air conduit to the fore-hearth car will be heated to a higher temperature by coming in contact with the slag in the fore-hearth car 16 when the furnace is in operation, this air which has been heated by contact with the slag passing to twyers 19, which direct it to the bottom of the shaft. 90

The fore-hearth car 16 is provided with an outlet 20 leading to a spout 21 which is mounted at the opening in the compartment 5. The metal is discharged from the crucible car 17 at an outlet 22 which communicates 95 with an outlet 23 in the compartment 5.

The outlets 20 and 22 are milled to fit against the outer walls of the compartment 5, and the track on which the cars 16 and 17 are disposed is preferably built at a 100 slight angle to the compartment 5 to tighten the joint between the outlets 20 and 22 and the walls of the compartment.

When the smelting furnace is in use the spout 21 is sealed by the slag flowing from the fore-hearth car 16 and the spout 23 is sealed by the matte flowing from the crucible car 17. The air entering the opening 12, passes up in the air space 9, the walls 7 and 8 serving to keep the wall reasonably 110 cool, the air becoming heated and flowing through the air conduit 13 to the compartment.

ment 5, where it is further heated by the slag in the fore-hearth car 16. The matte settles at the bottom of the crucible car 17 and the slag passes over the outlet 18 to 5 the fore-hearth car 16.

Having thus described my invention, I claim as new, and desire to secure by Letters Patent:

1. In a smelting furnace, a compartment 10 having an opening, a shaft having double walls forming an air space, the inner wall being connected with the compartment at the opening, there being an opening in the outer wall of the shaft adjacent the compartment serving as a cold air inlet leading to the air space, a crucible car in the compartment, means for directing slag from the crucible car, and an air duct leading from the air space at the top of the shaft to 15 the interior of the compartment.

2. In a smelting furnace, a compartment having a shaft opening and opposite sides with an outlet opening in each of its said sides, a shaft connected with the compartment at the shaft opening, tracks in the compartment adjacent one of the said sides and disposed at an angle relatively thereto, a crucible car on the tracks, tracks in the compartment adjacent other of the said 20 sides and disposed at an angle thereto, a fore-hearth car in the compartment on the last mentioned tracks, means for directing slag from the upper portion of the crucible car to the fore-hearth car, a spout at the 25 bottom of the crucible car fitting one of the outlet openings in the compartment, a spout at the bottom of the fore-hearth car fitting

the other outlet opening in the compartment, and an air duct leading from the shaft to the interior of the compartment. 40

3. In a smelting furnace, a compartment having a shaft opening and two outlet openings at its sides, a shaft connected with the compartment at the shaft opening, a crucible car in the compartment under the 45 shaft, a fore-hearth car in the compartment at the side of the crucible car, means for directing slag from the upper portion of the crucible car to the fore-hearth car, a spout at the bottom of the crucible car 50 fitting one of the outlet openings in the compartment, a spout at the bottom of the fore-hearth car fitting the other outlet opening in the compartment, and an air duct leading from the top of the shaft to 55 the interior of the compartment.

4. In a smelting furnace, a compartment having an opening, a shaft having double walls forming an air space, the inner wall being connected with the compartment at 60 the opening, a cold air duct at the top of the compartment around the shaft, there being an opening in the outer wall of the shaft affording communication between the cold air duct and the air space, a crucible 65 car in the compartment under the shaft, a fore-hearth car in the compartment at the side of the crucible car, an air duct leading from the air space at the top of the shaft to the interior of the compartment adjacent the fore-hearth car, and means for directing slag from the crucible car to the 70 fore-hearth car.

THOMAS ARTHUR M. STEVENSON.
